US0D1026809S

(12) **United States Design Patent** (10) **Patent No.:** **US D1,026,809 S**
(45) **Date of Patent:** **** May 14, 2024**

(54) **CHARGER**

(71) Applicant: **Arctic Fox (Dongguan) Information Technology Co., Ltd.**, Dongguan (CN)

(72) Inventor: **Xiaohui Lu**, Dongguan (CN)

(73) Assignee: **Arctic Fox (Dongguan) Information Technology Co., Ltd.**, Dongguan (CN)

(**) Term: **15 Years**

(21) Appl. No.: **29/918,345**

(22) Filed: **Nov. 27, 2023**

(51) LOC (14) Cl. **13-02**
(52) U.S. Cl. **D13/107**

(57) **CLAIM**

The ornamental design for an charger, as shown and described.

DESCRIPTION

FIG. 1 is a front and top perspective view of a charger, according to a first embodiment; and in a closed configuration;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom perspective view thereof;

FIG. 9 is a rear and left perspective view thereof, in an open configuration;

FIG. 10 is a front and top perspective view of a charger, according to a second embodiment; and in a closed configuration;

FIG. 11 is a rear and bottom perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof;

FIG. 17 is a bottom perspective view thereof;

FIG. 18 is a rear and left perspective view thereof, in an open configuration;

FIG. 19 is a front and top perspective view of a charger, according to a third embodiment; and in a closed configuration;

FIG. 20 is a rear and bottom perspective view thereof;

FIG. 21 is a front elevational view thereof;

FIG. 22 is a rear elevational view thereof;

FIG. 23 is a left side elevational view thereof;

FIG. 24 is a right side elevational view thereof;

FIG. 25 is a top plan view thereof;

FIG. 26 is a bottom perspective view thereof; and,

FIG. 27 is a rear and left perspective view thereof, in an open configuration.

The broken lines in the drawings depict portions of the charger that form no part of the claimed design.

1 Claim, 27 Drawing Sheets
